UNITED STATES PATENT OFFICE.

ARTHUR F. PYM, OF LYNN, MASSACHUSETTS, ASSIGNOR TO UNITED SHOE MANUFACTURING CORPORATION, OF PATERSON, NEW JERSEY, A CORPORATION OF NEW JERSEY.

MACHINE FOR SMOOTHING SHOE LININGS.

Application filed November 25, 1921. Serial No. 517,534.

To all whom it may concern:

Be it known that I, ARTHUR F. PYM, a subject of the King of England, and resident of Lynn, in the county of Essex and State of Massachusetts, have invented certain Improvements in Machines for Smoothing Shoe Linings, of which the following description, in connection with the accompanying drawings, is a specification, like reference characters on the drawings indicating like parts in the several figures.

This invention relates to machines or devices for applying a smoothing or stretching tension to the materials of shoes after the sole-attaching operation, and is illustrated as embodied in a machine for smoothing the linings of shoes which have been turned and relasted.

In making a turn shoe, the lining is outside the remainder of the upper materials when the shoe is stretched over the first last. Consequently after the shoe has been turned right side out, there is sufficient fullness in the lining to allow it to wrinkle or bunch up when the second last is inserted. It has always been necessary, therefore, to smooth out the lining after the insertion of the second last.

Heretofore this operation has invariably been performed by hand, the operator holding the shoe in one hand and with the other manipulating a thin blunt-edged implement known as a "lining knife." This implement is inserted between the shoe and last, and twisted or oscillated as it is moved about, progressively to stretch out narrow areas of the lining in a manner to remove the wrinkles or bunches. The operation is not a "smoothing" operation in the sense that the wrinkles are merely rubbed or flattened down as they are rather removed by progressively stretching out the lining and distributing it more equally about the last. The operation also tends to stretch out the shoe materials generally, in a manner to remove and distribute any uneven strains introduced by inserting the second last. It will be appreciated that this smoothing or stretching operation is very laborious, as only one hand can be used,

and the strain of twisting the lining knife all comes on the relatively weak wrist muscles.

In view of these conditions, an object of my invention is to lighten the labor of so stretching out the shoe materials to smooth the lining and for other purposes. From this point of view, therefore, my invention may be regarded as consisting in an organization comprising the combination of a stretching implement such as a "lining knife", as such an implement is commonly termed in the trade, with a mounting therefor such as to permit a shoe to be held in both hands when presented thereto, and to eliminate the necessity for twisting the knife by hand. While the illustrated machine embodies a lining knife shaped like those used in the hand operation, the invention is not especially concerned with the specific form of implement used, and the expression "lining knife" will be used in a generic sense to denote any suitable smoothing or stretching instrumentality.

In the embodiment of the invention illustrated in the accompanying drawings, a lining knife is mounted for a twisting or oscillating motion about a longitudinal axis, and suitable connections from a rotary power shaft are provided for actuating the knife. As a result of the twisting movement of the knife, the lining is smoothed or stretched by movement of the lining relatively to the last and the shoe upper, and the wrinkles are substantially eliminated therefrom. In order to stretch the shoe materials in opposite directions as occasion demands, a manually controlled lever is provided for reversing the direction of the twisting or oscillating motion; and to prevent injury to the work, the knife-actuating connections comprise opposed springs through which the knife is yieldingly operated. In order to adapt the machine for shoes of different sizes and of varying tightness on their lasts, means is provided under the operator's control, for varying the extent of the oscillating movements of the lining knife.

The above and other objects and features

of the invention, including specific constructions and combinations of parts, will be apparent from the following description of the embodiment of my invention illustrated in the accompanying drawings, in which:

Fig. 1 is a front elevation, and Fig. 2 is a side elevation, of a machine embodying an illustrative form of my invention.

The machine comprises generally a base 10 of any desired form, on which is mounted a head 12 having formed therein a suitable bearing for a rotatable tool holder 14. In this holder there is secured, as by set-screws 16, an elongated implement illustrated as a lining knife 18, for stretching out and distributing about a last the lining and other upper materials of a shoe thereon, as above explained.

Clamped about the opposite end of holder 14 is an arm 20, arranged to be oscillated by a link 22 formed with sleeves 24 and 26 which engage a pitman 28. In order to avoid possible injury to a shoe operated on thereby, the lining knife or equivalent implement 18 is arranged to be actuated yielding by providing springs 30 and 32 surrounding pitman 28 and engaging opposite sides of sleeve 24. These springs are confined between sleeve 24 and stops 34 and 36 adjustably clamped on pitman 28, and thus the movement of the pitman is transmitted through the springs and link 22 to the holder and the lining knife mounted therein.

The pitman is reciprocated by a lever 38 which is constantly oscillated by link 40 secured to a crank pin on gear 42, meshing with a second gear 44 on drive shaft 46. This shaft is rotated by a suitable pulley 48, or equivalent means, acting through any desired form of clutch such as shown at 50. The clutch is illustrated as being controlled by a treadle 52 which is locked down by bell-crank 54 until the operator trips the bell-crank by stepping on the projecting arm 56.

In order to control the extent and direction of the twisting motions or oscillations imparted to the lining knife 18 by the above-described mechanism, pitman 28 is arranged to be actuated by different portions of lever 38, at varying distances from the fulcrum, thus varying the extent of oscillation or "throw" of the lining knife, and also on opposite sides of the fulcrum, thus changing the direction of the oscillations or twisting motions.

As one way of arranging this in a manner to be controlled by the operator during the operation of the machine, while leaving both his hands free to manipulate the work, a knee lever 60 may be mounted to turn about its fulcrum 62 to reciprocate a rack 64 by means of a pin-and-slot connection. A pinion 66 meshing with this rack transmits its motion through shaft 68 to a pinion 70

which is mounted concentrically with respect to the axis about which lever 38 turns. Pinion 70 meshes with a curved rack 72 sliding in an undercut groove in lever 38. Pitman 28 is connected to the center of this curved rack at 74. Thus motion of the knee lever is utilized to slide rack 72 back and forth to vary the distance of connection 74 from the axis of shaft 68, thus varying the throw of pitman 28; and to change connection 74 from one side to the other of this axis, thus reversing the direction of its motion. It will be noted that at an intermediate point this connection 74 will align with shaft 68, so that there will be no motion of pitman 28.

In practice, clutch 50 is usually actuated only to stop and start the machine at the beginning and end of a run of work such as a rack of relasted shoes. The shoes are presented successively to the machine by the operator, who has both hands free to manipulate them. The lining knife is entered between the last and shoe with connection 74 at its intermediate or idle position, and lever 60 is then operated to move this connection to one side or other of shaft 68 to any desired extent, whereupon a twisting or oscillating motion is yieldingly imparted to lining knife 18.

As is well known to those skilled in the art, it is usual to twist a lining knife in opposite directions at times when operating on a shoe, as it is more effective to turn it away from a wrinkle which is being removed, and this may be accomplished on the illustrated machine by manipulating lever 60 to move connection 74 to opposite sides of shaft 68.

While one form of my invention has been illustrated and described, it is not my intention to limit its scope thereby, or otherwise than by the terms of the appended claims.

Having described my invention what I claim as new and desire to secure by Letters Patent of the United States is:

1. In a machine for smoothing the linings of relasted shoes, in combination, a member constructed and arranged to be inserted between a last and a shoe completely relasted thereon, and a mounting for said member constructed and arranged to enable the member to be operated to smooth out the lining of a shoe and to permit a shoe to be held in both hands when presented in position to be operated upon by said member.

2. In a machine for smoothing the linings of relasted shoes, in combination, a member to be inserted between a last and a shoe thereon, and means yieldingly to twist said member to smooth out the lining of the shoe.

3. In a machine for smoothing the linings of relasted shoes, in combination, a member to be inserted between a last and a shoe

- thereon and constructed and arranged to permit relative movement of the shoe and said member while the machine is operating to smooth the lining and to transfer the 5 point of operation of said member to different parts of the shoe, and manually controlled power means to operate said member to smooth out the lining of the shoe.
4. In a machine for operating on relasted 10 shoes, in combination, a flat member to be inserted between a last and a shoe thereon, and means to twist said member back and forth about a longitudinal axis to stretch out and smooth the lining of the shoe.
- 15 5. In a machine for operating on shoes, in combination, an elongated lining knife constructed and arranged to enter between a last and a shoe after the shoe has been completely relasted thereon and to project a 20 substantial distance into the inside of the shoe, a rotary shaft, and connections from said shaft to operate the knife to smooth out the lining of a shoe.
- 25 6. In a machine for operating on shoes, in combination, a lining knife, a power shaft, and connections including opposed springs yieldingly to twist the knife back and forth about its axis.
- 30 7. In a machine for use in making shoes, in combination, means engageable with the exterior of a last progressively to engage and stretch or smooth out various portions of the lining of a shoe on the last, and operator-controlled mechanism to actuate said means.
- 35 8. In a machine for use in making shoes, in combination, an oscillatory member constructed and arranged to engage and smooth out the lining of a substantially finished shoe, mechanism to oscillate said member, and operator-controlled means to vary the extent of the 40 oscillations.
- 45 9. In a machine for use in making shoes, in combination, a member to engage and smooth out the lining of a shoe, mechanism to oscillate said member, and operator-controlled means to vary the direction of the oscillations with respect to a neutral position.
- 50 10. In a machine for use in making shoes, in combination, a member to engage and smooth out the lining of a shoe, mechanism to oscillate said member, and operator-controlled means to vary the extent and direction of the oscillations.
- 55 11. In a machine for use in making shoes, in combination, a holder mounted for oscillation about a longitudinal axis, and a readily-detachable instrumentality carried thereby and arranged to engage the inside of a shoe and be oscillated back and forth while 60 inside the shoe.
- 65 12. In a machine for operating on shoes, in combination, a lining knife, a rotary shaft, connections from said shaft to oscillate the knife about a longitudinal axis to 65 smooth out the lining of a shoe, and a manually-operable device to control said connections to vary the extent of the oscillations.
- 70 13. In a machine for operating on shoes, in combination, a lining knife, a rotary shaft, connections from said shaft to oscillate the knife about a longitudinal axis to smooth out the lining of a shoe, and a manually-operable device to control said connections to vary the direction of the oscillations. 75
- 80 14. In a machine for operating on shoes, in combination, a lining knife, a rotary shaft, connections from said shaft to oscillate the knife about a longitudinal axis to smooth out the lining of a shoe, and a manually-operable device to control said connections to vary the extent and direction of the oscillations. 85
- 90 15. A machine of the class described comprising, in combination, an elongated member successively to engage a series of restricted areas of the inside of a substantially finished shoe, and means to rock said member about a longitudinal axis as it engages each such area to stretch the shoe materials engaged thereby.
- 95 16. A machine of the class described comprising, in combination, means engageable with the exterior of a last for imparting a series of stretching impulses against the inside of a shoe on the last, and operator-controlled means to vary the extent of the impulses. 100
- 100 17. A machine of the class described comprising, in combination, means engageable with the exterior of a last for imparting a series of stretching impulses against the inside of a shoe on the last, and operator-controlled means to vary the direction of the impulses. 105
- 110 18. A machine of the class described comprising, in combination, means engageable with the exterior of a last for imparting a series of stretching impulses against the inside of a shoe on the last, and operator-controlled means to vary the extent and direction of the impulses.
- 115 19. A machine for operating on shoes after the soles have been attached to the upper materials and while the shoes are on their lasts comprising, in combination, mechanically-actuated means to engage and stretch the upper materials successively at opposite 120 sides of the shoe, and auxiliary manually-operable means to control the operation thereof.
- 125 20. A machine for operating on shoes after the soles have been attached to the upper materials and while the shoes are on their lasts, comprising, in combination, a member to engage a restricted area of a shoe and movable in a direction to apply tension to the shoe materials, and a mounting therefor per- 130

mitting relative movement of said member and a shoe progressively to apply tension to widely separated parts of the shoe materials.

21. A device for smoothing the lining of a relasted turned shoe comprising, in combination, an elongated lining knife to be inserted between a shoe and a last, after the shoe has been completely relasted, and a

mounting for said knife permitting an operator manually to present a shoe thereto and move it about relatively thereto, progressively to smooth the lining.

In testimony whereof I have signed my name to this specification.

ARTHUR F. PYM.
